UNITED STATES PATENT OFFICE.

HOWARD GRATZ BROWER, OF CHATTANOOGA, TENNESSEE, ASSIGNOR OF ONE-HALF
TO PORTER WARNER, OF CHATTANOOGA, TENNESSEE.

SOAP AND WATER MIXER.

Application filed August 7, 1923. Serial No. 656,230.

To all whom it may concern:

Be it known that HOWARD GRATZ BROWER, citizen of the United States, residing at Chattanooga, in the county of Hamilton and

5 State of Tennessee, has invented certain new and useful Improvements in Soap and Water Mixers, of which the following is a specification.

This invention relates to certain new and 10 useful improvements in a soap and water mixer and has for its principal object the provision of a mixer whereby a predetermined amount of soap may be used to cause the proper mixture for a solution of soap 15 and water.

A further object of this invention is to provide a soap and water mixer whereby a solution of water will be caused to pass through a container of soap and dispense 20 therefrom thoroughly mixed.

Another object of the invention is to provide a soap and water mixer capable of being used in various places where a solution of soapy water is desired.

25 Further objects and advantages of my invention will appear from the more detailed description set forth below, illustrated in the accompanying drawing, and pointed out in the claim.

30 In the drawing,—

Figure 1 is an elevational view of my improved soap and water mixer as made in accordance with this invention, showing it assembled and ready for use,

35 Figure 2 is a top plan view of the soap and water mixer disconnected from the water supply source,

40 Figure 3 is an elevational view partly in section showing the relative position of the soap container with the water container,

Figure 4 is a side elevational view of the soap container, and,

45 Figure 5 is a fragmentary, elevational view illustrating a hose connection at the outlet end of the container.

Referring more particularly to the drawing, the soap and water mixer in its preferred form includes a cylindrical body 5 having one end substantially funnel-shaped

50 as at 6, and equipped to receive a hose or other pipe connections as at 7. The funnel-shaped end 6 constitutes an outlet for the water in the container 5 and the opposite end of this container is provided with an

55 annular exterior flange 8, to which is re-

movably secured a funnel-shaped head member 9, the head member 9 being removably secured to the annular flange 8 of the container 5 by suitable fastening means 10.

The fastening members 10 shown on the drawing, are in the form of a wing nut and bolt but any preferable fastening means can be used. But as shown in the drawing, the bolts are permanently secured to the flange 8 and the head 9 is equipped with laterally extending diametrically opposed lugs 11, which embrace the bolts of the flange 8 and are held thereon by the wing nuts 12.

The central portion of the head 9 is provided with a threaded connection 13, which is detachably secured to a water supply source 14 which is controlled by a valve 15. The valve 15 controls the inlet of water from the pipe 14 through the head 9 into the container 5.

75 A reticulated cylinder 16 of a diameter smaller than the interior diameter of the container 5 is provided and is removably supported within the container 5 and is adapted to contain soap or soapy ingredients.

80 This reticulated cylinder 16 is provided with a closed end 17 and has formed on its closed end a plurality of relatively spaced L-shaped supporting brackets 18, and the 85 opposite end of this soap container is provided with an annular flared flange 19, which is of a diameter greater than the interior diameter of the container 5 and is adapted to rest upon the annular flange 8 of the container 5 so as to removably support the cylinder 16 within the container 5 in such a position that the water entering through the head 9 will first pass through the reticulated cylinder 16 mixing with the 90 soap solution prior to passing out of the funnel-shaped end 6.

95 The brackets 18 engage the container 5 at the point of juncture with the funnel-shaped end 6 so as to relatively support the cylinder 16 in its proper position within the container 5 and consequently hold this reticulated cylinder against lateral movement in any direction.

100 It is to be understood that a hose 20 can be detachably secured to the connection 7 of the funnel-shaped end 6 of the container 5 so as to permit the water and soap solution of the container to be sprayed at any desired point.

It is apparent that I have provided a compact, inexpensive and convenient soap and water mixer which allows a steady and uniform flow of soap and water mixture and 5 at the same time permits the easy removal of the soap container so that plain water may be used to rinse the article which has received the soap and water mixture.

It is further obvious that the mixture set 10 forth is not limited in its application to soap and water mixtures only, but it can be used for making various solutions or emulsions of any desired substance in water or another solvent or vehicle.

15 Having thus described my invention, what I claim as new is:

A soap and water mixer comprising a cylindrical container having a funnel-

shaped outlet end, a removable head having a water connection for the opposite end of 20 said container, means to removably connect the head to said container, a reticulated soap cylinder having one end closed, supporting brackets secured to said closed end, a flange at the opposite end of said reticulated cylinder, said flange interposed between 25 said head and open end of the container, said brackets engaging the container at its point of juncture with the funnel-shaped outward end, said brackets and flange 30 positioning the reticulated soap cylinder in spaced relation within the container.

In testimony whereof he hereunto affixes his signature.

HOWARD GRATZ BROWER.
